UNITED STATES PATENT OFFICE.

CHARLES A. THOMPSON, OF EAST NEW YORK, ASSIGNOR OF ONE-THIRD
HIS RIGHT TO GEORGE F. ANDERSON, OF NEW YORK CITY.

IMPROVEMENT IN UMBRELLA-RUNNERS.

Specification forming part of Letters Patent No. 147,804, dated February 24, 1874; application filed November 22, 1873.

To all whom it may concern:

Be it known that I, CHARLES A. THOMPSON, of East New York, Kings county and State of New York, have invented new and useful Improvements in Umbrella-Runners; and I do hereby declare the following to be a full, clear, and exact description thereof, reference being had to the accompanying drawings, forming a part of this specification, in which—

Figure 1 is a side elevation of my improved runner; Fig. 2, a longitudinal section of the same; and Fig. 3, a view of the under side of the runner.

Similar letters of reference indicate like parts in all the figures.

My invention relates to improved constructions and arrangements of the parts of an umbrella-runner, and in the mode of attaching it to the staff, so as to render it strong and durable, as well as neat in its appearance and efficient in its operation. It consists, first, in an improved construction and arrangement of the catch and spring, and in the mode of connecting the catch with the staff when the cover is raised or lowered; and, secondly, in an improved device for guiding the runner, so as to cause the catch properly and with certainty to enter the slot provided in the staff to receive the same.

In the drawing, A represents the runner, having a tubular portion, a, which fits and works upon the staff B of the umbrella, and a flange, b, provided with radial slots to receive the ribs in the ordinary manner. C is a straight steel spring, one end of which is riveted, soldered, or otherwise secured to the tubular portion of the runner, as seen at d, and to the other end of the said spring is attached the catch D. This catch D is made substantially in the form shown in the drawing, and is provided with a projecting portion, e, which, passing through a perforation in the tubular portion of the runner, enters a slot, f, provided in the staff to secure the runner in position when the umbrella is either raised or lowered, the said slots being located in suitable positions for that purpose. The flange b is located a short distance from the upper end of the tube a, as shown in the drawing, and on that portion of the tube a which extends above or beyond the said flange, is provided a tapering slot, h, made to receive a pin, i, by which means the runner is prevented from

turning on the staff, and the projection e of the catch D is brought directly over the slot f. The pin i also serves as a stop when the umbrella is raised, in which position it is shown in Figs. 1 and 2. A slot, h', similar to the slot h, may be provided on the lower end of the tube a to receive a pin, i', for guiding the runner, so that the projection on the catch D will enter a slot provided on the lower part of the staff B when the umbrella is lowered. When the umbrella is extended, the flange f comes in contact with the pin i, and the said pin is within the slot h, as shown in the drawings, and, when the umbrella is lowered, the pin i' comes within the slot h'.

Other similar devices may also be employed for guiding the runner, so that the slot f shall come directly under the projection e of the catch, as, for instance, a tapering projection may be provided on the upper end of the tubular portion of the runner, to enter a ring secured to the staff, which will prevent the runner from turning on the staff, and insure the catch entering the slot.

An umbrella-runner, constructed as herein shown and described, is strong, compact, and durable, not liable to get out of order, and is very certain in its operation, and neat in appearance.

I am aware that a catch similar to the catch D has been before used on an umbrella-runner, but attached to the runner and spring, and operating in a different manner, as shown in the patent of Horace Hotchkiss, No. 50,587. This I do not claim; but

What I claim as my invention is—

1. The catch D, constructed as described, and mounted upon the straight spring C, the latter being attached thereto and secured to the runner in the manner specified, in combination with the slot f, pin i, and runner A, having a slot, h, in the tubular portion thereof, all the several parts being arranged in relation to each other, as described, for the purpose set forth.

2. In an umbrella-runner, the slot h, in combination with the pin i and slot f in the staff B, as herein shown and described, for the purposes specified.

CHARLES A. THOMPSON.
